known that we, George W. Sizer and Henry Sizer, of Springfield, in the County of Hampden, and State of Massachusetts, have invented or produced a new and ornamental stove, which we denominate "Sizers Summer and Winter Double Oven airtight Stove," and we do hereby declare the following to be a full and exact description of the same, reference being had to the accompanying drawings making a part of this specification.

The nature of our invention consists in the production of an ornamental stove by the combination of the several designs and configurations on the various parts thereof, as herein set forth. Fig. 1, in the accompanying drawings, is a perspective elevation of our ornamental stove; the top plate of the same is ornamented around its edge by a fancy moulding, of which an enlarged view is shown in fig. 3. The front plate *E*, of the stove is ornamented by a convoluted, fluted surface, surmounted by a panel having the words Sizer & Co. Springfield Mass, cast upon the same; at the base of the front plate *E*, there projects a hearth *g*, surrounded by a moulding of the same pattern as that surrounding the top plate of the stove. The furnace door, *C*, has the words Summer and Winter, cast upon it, over the damper. The ash pit hearth *e*, is connected to, or cast with the over door, *d*; the sliding ash pit cover, has the words Sizers Double Oven airtight Cooking Stove, patented 1845. The front side plate of the stove is ornamented on each side of the furnace door *C*, by a representation of strings or cords, arranged in a vertical position, uniting ornamental bases and caps. On the right hand projecting corner *h*, of the front side plate, there is a design representing scrolls united by foliage.

Fig. 2, is an elevation of the rear side plate of the stove; *a*, is a panel opposite the furnace door *C*, ornamented by a couple of the same designs (scrolls united by foliage) that are carved or cast upon the projection *h*, on the front plate of the stove; *b*, is a rear oven door (or panel) having the same ornamental designs as the panel *a*, above it; *h*, is a projection having the same ornamental device upon it, as the corresponding projection on the front plate of the stove.

What we claim as original and desire to secure by letters Patent,
